METHOD AND APPARATUS FOR
ANALYZING FLUE GASSherman Chase, Evergreen Park, Ill., assignor to
Carnegie-Illinois Steel Corporation, a corpora-
tion of New Jersey

Application January 13, 1945, Serial No. 572,715

8 Claims. (Cl. 23—232)

1

This invention relates to a method and apparatus for combustion control by using fractional or incremental combustion principles in cascade. Liquid, solid and gaseous fuels, which are used in combustion chambers and the like, vary in quality and quantity, thus requiring continuous adjustment of the rate at which air is supplied. In some cases more than one fuel is burned, this requiring a multiplicity of summarizing devices. Various types of controls are in use at present, but they are all relatively complicated and expensive. In some cases, particularly when the air requirements are relatively constant, the flue gas is analyzed in order to determine whether or not the correct amount of air is being supplied to the burner and the air supply is then controlled manually. The apparatus used to analyze the flue gas is also relatively complicated and expensive.

It is an object of my invention to provide a method and apparatus for controlling the ratio of air to fuels within practical limits of economy and desirability in order to obtain in a simple manner substantially perfect combustion.

Another object of my invention is to provide simple means for analyzing flue gas.

These and other objects will be more apparent after referring to the following specification and attached drawings, in which:

Figure 1 is a schematic diagram showing one embodiment of my invention;

Figure 2 is a schematic diagram showing a second embodiment of my invention; and

Figure 3 is a schematic diagram showing a third embodiment of my invention.

Referring more particularly to Figure 1 of the drawings, reference numeral 2 indicates a stack or other source of flue gas from which a suitable sample of the gas is drawn through a conduit 4 by a gas pump 6 mounted on a shaft 8. The flue gases will enter the pump at approximately room temperature and while this temperature will vary slightly, the rate of change will be slow so that comparable results are obtained. A pulley 10 is fastened to the shaft 8 and is driven by means of a belt 12 which passes around a pulley 14 mounted on the shaft of a motor 16. The flow of gas will be at a constant rate since no means is provided for varying the speed of motor 16. A constant increment of hydrogen is added to the flue gas in the conduit 4 from an electrolytic cell 18 and the pump 6 delivers the mixture of flue gas and hydrogen through a pipe 20 to a conduit 22. Within the conduit 22 are three platinum resistors 24, 26 and 28 through which current passes

from a source of current 30. The resistors 24 and 26 each form one leg of a Wheatstone bridge, the other legs being resistors 32 and 34. A galvanometer 36 in the Wheatstone bridge may be calibrated to indicate the amount of excess air or the amount of carbon monoxide. Between the resistors 24 and 26 is an inlet 38 through which oxygen is admitted from the electrolytic cells 40 and 42. Power is delivered to the electrolytic cells 18, 40 and 42 through the lines 44. Between the resistors 26 and 28 is an inlet 46 through which hydrogen is introduced from the electrolytic cells 40 and 42, the volume of hydrogen being twice that of the oxygen. From the conduit 22 the mixture of gases passes through a cooler 48 to a gas pump 50 mounted on the shaft 8 and which has the same volume characteristics as pump 6 so that for each rotation of shaft 8, the volume of gas pumped by either pump is equal. A suitable type of pump for this purpose is one constructed according to the principles of a wet type gas meter, which, when rotated by a source of power, is capable of acting as a gas pump. A pipe 52 leads from the suction end of pump 6 to a diaphragm chamber 54 whose diaphragm transmits the pressure from the suction side of pump 6 to a beam 56 which is suitably pivoted at 58. A pipe 60 leads from the suction end of pump 50 to a diaphragm chamber 62, whose diaphragm transmits pressure from the suction side of pump 50 to the beam 56 to oppose the pressure exerted by the diaphragm in chamber 54. The beam 56 is suitably counterbalanced by spring 64 and counterweight 66. The pressure of spring 64 may be adjusted by means of a screw 68 which is threaded through a suitable support 70. On its free end the beam 56 carries an electrical contact 72 having a wire 74 connected thereto and which is movable with the beam 56 to contact one of the electrical contacts 76 and 78 to deliver current to the motor armature 80. Current is supplied to the armature 80 and field 82 from the power lines 83 through the switch 84. The armature shaft of the motor carries a pinion 85 which meshes with a gear 86 mounted on a shaft 88. A lever 90 is also mounted on the shaft 88 and through linkage 92 and 94 changes the position of valve 96 in the air line 98.

The operation of the device is as follows: The pump 6 delivers the mixture of flue gas and hydrogen to the conduit 22. If there is free oxygen in the flue gas, it combines with the hydrogen in the mixture to form water vapor as it passes over the heated resistor 24, thus reducing the volume of the mixture an amount equal to

three times the volume of the oxygen. The burning of the hydrogen and oxygen develops heat which changes the resistance of resistor 24 to unbalance the Wheatstone bridge and the galvanometer 36 will indicate the amount of excess air. The oxygen entering at 38 and the hydrogen entering at 46 will combine to form water vapor and will have no effect on the volume of the sample. The flue gas from the conduit 22 passes through the cooler 48 in order to bring its temperature down to that of the flue gas drawn into pump 6 and passes into the pump 50. Since the gas entering the pump 50 has a smaller volume than that entering the pump 6, the pressure on the diaphragm 62 will be less than that on diaphragm 54, thus completing a circuit through contactors 72 and 78 to motor 80 which operates to close air valve 96 to decrease the amount of air supplied to the combustion chamber.

If, instead of an excess of oxygen, the flue gas contains a combustible such as carbon monoxide, the carbon monoxide will combine with the oxygen added at 38 as it passes over the heated resistor 26 without any reduction in the volume of the flue gas. The remaining oxygen combines with hydrogen and there will be an increase in volume equal to the amount of carbon monoxide since for each volume of carbon monoxide burned there will remain one volume of hydrogen lacking oxygen for combustion. This increase in volume causes the pressure to build up at 60 so that the pressure on diaphragm 62 is greater than that on diaphragm 54, this completing a circuit through contactors 72 and 76 to motor 80 which rotates in the direction opposite to that above to cause the valve 96 to open to increase the supply of air to the combustion chamber. The burning of the combustibles at resistor 26 changes the resistance of the resistor, this unbalancing the Wheatstone bridge and the galvanometer 36 will indicate the amount of carbon monoxide.

The analyses of any commercial fuel is such that when it burns, sufficient H_2O is formed so that the flue gas when cooled to room or atmospheric temperature will be saturated with water vapor. Furthermore, since the gas sample passes through the wet type gas pump 6 it necessarily becomes saturated. Since the cooler 48 reduces the temperature of the gas to room temperature, the H_2O will not be in the form of steam and the decrease in volume will be that set forth above, since the H_2O will not be in the form of gas and its volume will be negligible. Whether carbon monoxide or oxygen is present in the flue gas determines whether the volume of the sample going through the combustion tube will increase or decrease. If excess oxygen is present, the volume will decrease as set forth above and if carbon monoxide is present, the volume will increase since the hydrogen added at 46 will not all burn or combine.

Figure 2 shows a second embodiment of my invention which differs from that of Figure 1 in the means employed for utilizing the results of the incremental combustion of the flue gas to control the air flow. The pumps 6 and 50 are omitted and the apparatus described hereinafter substituted therefor. A conduit 99 is used in place of conduit 22 and is similar thereto in that it contains resistors 24, 26 and 28 and associated Wheatstone bridge and also has the same apparatus for adding oxygen and hydrogen. Hydrogen is added from the electrolytic cell 18 into the conduit 99 through nipple 100. Between nipple 100 and resistor 24 is an orifice plate 102 and

at the other end of conduit 99 is a second orifice plate 104 having an orifice about twice the area of that of orifice plate 102. There is a by-pass 106 around the orifice plates 102 and 104 having a fluid chamber 108 therein. A siphon 110 draws a sample into conduit 99 and if more than the desired amount of flue gas is drawn, it will bypass around the orifice plates 102 and 104 and bubble through the water in the chamber 108. A pressure line 112 is located in the conduit on the entry side of orifice 104 and leads to a diaphragm 114 which transmits the pressure to a beam 116 which is pivotally mounted at 118. The beam 116 is counterbalanced by means of counterweight 122 and spring 120 which may be adjusted by means of screw 124 threaded through a suitable support 126. The beam 116 carries the contactor 72 which is adapted to contact contactor 76 or 78 of the motor circuit according to the pressure in the line 112.

The operation of the device is as follows:

The differential across an orifice is proportional to the product of volume and total weight of the gases flowing therethrough and if there is an excess of oxygen in the flue gas the volume of the flue gas contracts causing a decrease in differential across orifice 104, this completing a circuit through contactors 72 and 76 to motor 80 which operates to close air valve 96 to decrease the supply of air. If carbon monoxide or other combustibles are in the flue gas instead of free oxygen, the volume of the gas going through orifice 104 increases, this increasing the differential across the orifice and completing a circuit through contactors 72 and 78 to motor 80 causing it to rotate in the reverse direction to open air valve 96. The Wheatstone bridge is provided with a galvanometer to indicate the amount of oxygen or combustible in the flue gas in the manner described above.

In the embodiment shown in Figure 3, the heat generated by the combustion of the gases is used to control the flow of air in addition to indicating whether or not there is excess oxygen in the flue gas. A sample of flue gas is drawn from the stack 2 by means of a pump 128 and delivered through a pipe 130 to a conduit 132. The pipe 130 is provided with an outlet 134 for getting rid of excess flue gas. Within the conduit 132 are two platinum resistors 136 and 138, each of which forms one leg of a Wheatstone bridge, the other legs being resistors 140 and 142. Power is supplied to the resistors through lines 144 and a potentiometer controller 146 is provided in the Wheatstone bridge and is connected to control the circuit of air valve motor 80 in the usual manner. Hydrogen is supplied to the conduit 132 through an inlet 148 from an electrolytic cell 150. Between the resistors 136 and 138 is an inlet 152 through which oxygen is supplied to conduit 132 from electrolytic cells 150 and 154. Power is delivered to the electrolytic cells 150 and 154 through the lines 156.

The operation of the device is as follows:

If there is free oxygen in the flue gas, it combines with the added hydrogen to form water vapor as it passes over the heated resistor 136. The burning of the hydrogen and oxygen develops heat which changes the resistance of resistor 136 to unbalance the Wheatstone bridge and the potentiometer controller 146 then operates to complete a circuit through contactors 72 and 78 to motor 80 which operates to close the air valve 96 to decrease the amount of air supplied to the combustion chamber. If, instead of

an excess of oxygen, the flue gas contains a combustible such as carbon monoxide, the carbon monoxide will combine with the oxygen added at 152 as it passes over the heated resistor 138. The burning of the carbon monoxide develops heat which changes the resistance of resistor 138 to unbalance the Wheatstone bridge and the potentiometer controller 146 then operates to complete a circuit through contactors 72 and 76 to motor 80 which operates in the reverse direction to open the air valve 96 to increase the amount of air supplied to the combustion chamber. It will be understood that the potentiometer controller 146 may be replaced by a galvanometer which is calibrated to indicate the amount of excess air or the amount of carbon monoxide in the flue gas and this indication will be utilized by the operator to control the flow of air to the combustion chamber.

While several embodiments of my invention have been shown and described, it will be apparent that other adaptations and modifications may be made without departing from the scope of the following claims.

I claim:

1. The method of analyzing flue gas for the presence of free oxygen or a combustible therein which comprises sampling the flue gas at a constant temperature and at a constant flow rate, adding hydrogen to the flue gas sample at a constant flow rate, passing the resultant gas mixture at a constant flow rate to an analyzing zone, burning the hydrogen with any free oxygen in the flue gas in said zone, adding oxygen to the residual flue gas sample at a constant flow rate, burning any combustible in the residual sample with the added oxygen in said zone, and determining whether the original flue gas sample contains free oxygen or a combustible in response to the heat developed by the combustion of the gas.

2. The method of analyzing flue gas for the presence of free oxygen or a combustible therein which comprises sampling the flue gas at a constant temperature and at a constant flow rate, adding hydrogen to the flue gas sample at a constant flow rate, passing the resultant gas mixture at a constant flow rate to an analyzing zone, burning the hydrogen with any free oxygen in the flue gas on a first resistance heater in said zone, adding oxygen to the residual flue gas sample at a constant flow rate, burning any combustible in the residual sample with the added oxygen on a second resistance heater in said zone, measuring the change in resistance of the first and second resistance heaters in said analyzing zone to determine the presence of free oxygen or a combustible in the original flue gas sample.

3. The method of analyzing flue gas for the presence of free oxygen or a combustible therein which comprises sampling the flue gas at a constant temperature and at a constant flow rate, adding hydrogen to the flue gas sample at a constant flow rate, passing the resultant gas mixture at a constant flow rate to an analyzing zone, burning the hydrogen with any free oxygen in the flue gas on a first resistance heater in said zone, adding oxygen to the residual flue gas sample at a constant flow rate, burning any combustible in the residual sample with the added oxygen on a second resistance heater in said zone, adding hydrogen to the remaining flue gas sample at a constant flow rate the volume of the added hydrogen being twice that of the previously

added oxygen, burning the hydrogen with any free oxygen present in the flue gas mixture on a third resistance heater in said zone, condensing any water formed during the steps of burning hydrogen, and measuring the volume of the flue gas sample prior to passing said sample to the analyzing zone and subsequently to its exit therefrom to determine the presence of free oxygen or a combustible in the original flue gas sample.

- 5 10 4. The method of analyzing flue gas for the presence of free oxygen or a combustible therein which comprises sampling the flue gas at a constant temperature and a constant flow rate, adding hydrogen to the flue gas sample at a constant flow rate, passing the resultant gas mixture at a constant flow rate to an analyzing zone, burning the hydrogen with any free oxygen in the flue gas on a first resistance heater in said zone, adding oxygen to the residual flue gas sample at a constant flow rate, burning any combustible in the residual sample with the added oxygen on a second resistance heater in said zone, adding hydrogen to the remaining flue gas sample at a constant flow rate the volume of the added hydrogen being twice that of the previously added oxygen, burning the hydrogen with any free oxygen present in the flue gas mixture on a third resistance heater in said zone, condensing any water formed during the steps of burning hydrogen, determining the amount of free oxygen or a combustible present in the original flue gas sample.
- 15 20 5. The method of analyzing flue gas for the presence of free oxygen or a combustible therein which comprises sampling the flue gas at a constant temperature and a constant flow rate, adding hydrogen to the flue gas sample at a constant flow rate, passing the resultant gas mixture at a contact flow rate to an analyzing zone, burning the hydrogen with any free oxygen in the flue gas on a first resistance heater in said zone, adding oxygen to the residual flue gas sample at a constant flow rate, burning any combustible in the residual sample with the added oxygen on a second resistance heater in said zone, adding hydrogen to the remaining flue gas sample at a constant flow rate the volume of the added hydrogen being twice that of the previously added oxygen, burning the hydrogen with any free oxygen present in the flue gas mixture on a third resistance heater in said zone, condensing any water formed during the steps of burning hydrogen, measuring the change in resistance of the first and second resistance heaters in said analyzing zone to determine the presence of free oxygen or a combustible in the original flue gas sample.

- 35 40 6. Apparatus for analyzing flue gas which comprises a flue gas sampling means, a first source of hydrogen, a first conduit connecting said source to said flue gas sampling means, a second conduit which comprises a plurality of combustion zones connected to said sampling means, a first and second resistance heater located in said second conduit, a source of oxygen, a third conduit connecting said source of oxygen to said second conduit at a point between said first and second heaters, and means responsive to the change in resistance of the first and second resistance heaters for detecting the presence of oxygen or a combustible in the flue gas.

- 45 50 7. Apparatus for analyzing flue gas which comprises a flue gas sampling means, a first source of hydrogen, a first conduit connecting said source to said flue gas sampling means, a second

conduit which comprises a plurality of combustion zones connected to said sampling means, a first, second and third resistance heater located in said second conduit, a source of oxygen, a third conduit connecting said source of oxygen to said second conduit at a point between said first and second heaters, a second source of hydrogen, a fourth conduit connecting said second source of hydrogen to said second conduit at a point between said second and third heaters, and means responsive to the changes in the gas due to the combustion in the second conduit for detecting the presence of oxygen or a combustible in the flue gas.

8. Apparatus for analyzing flue gas which comprises a flue gas sampling means, a first source of hydrogen, a first conduit connecting said source to said flue gas sampling means, a second conduit which comprises a plurality of combustion zones connected to said sampling means, a first, second and third resistance heater located in said second conduit, a source of oxygen, a third conduit connecting said source of oxygen to said second conduit at a point between said first and second heaters, a second source of hy-

drogen, a fourth conduit connecting said second source of hydrogen to said second conduit at a point between said second and third heaters, and indicator means electrically connected to said first and second heaters differentially responsive to the change in resistance of the first and second heaters for detecting the presence of oxygen or a combustible in the flue gas.
